(57) **CLAIM**

The ornamental design for a golf cart rear canopy, as shown and described.

DESCRIPTION

FIG. 1 is a top perspective view of a golf cart rear canopy in an open position showing our new design;

FIG. 2 is a rear perspective view of the golf cart rear canopy shown in FIG. 1;

FIG. 3 is a front view of the golf cart rear canopy shown in FIG. 1;

FIG. 4 is a rear view of the golf cart rear canopy as shown in FIG. 1;

FIG. 5 is a right side view of the golf cart rear canopy shown in FIG. 1;

FIG. 6 is a left side view of the golf cart rear canopy shown in FIG. 1;

FIG. 7 is a top plan view of the golf cart rear canopy shown in FIG. 1;

FIG. 8 is a bottom plan view of the golf cart rear canopy shown in FIG. 1;

FIG. 9 is a front perspective view of the golf cart rear canopy in a closed or stored position;

FIG. 10 is a rear perspective view of the golf cart rear canopy shown in FIG. 9;

FIG. 11 is a front view of the golf cart rear canopy shown in FIG. 9;

FIG. 12 is a rear view of the golf cart rear canopy shown in FIG. 9;

FIG. 13 is a right side view of the golf cart rear canopy shown in FIG. 9;

FIG. 14 is a left side view of the golf cart rear canopy shown in FIG. 9;

FIG. 15 is a top plan view of the golf cart rear canopy shown in FIG. 9; and,

FIG. 16 is a bottom plan view of the golf cart rear canopy shown in FIG. 9.

The broken lines are shown for the purpose of illustrating parts of the article that form no part of the claim.

1 Claim, 9 Drawing Sheets
